UNITED STATES PATENT OFFICE.

ROBERT G. MacKINNON, OF NEW YORK, N. Y.

SELF-LEVELING TABLE.

No. 926,665.

Specification of Letters Patent.

Patented June 29, 1909.

Application filed September 10, 1908. Serial No. 452,403.

To all whom it may concern:

Be it known that I, ROBERT G. MacKINNON, a citizen of the United States, residing at New York city, in the county of New

5 York and State of New York, have invented new and useful Improvements in Self-Leveling Tables, of which the following is a specification.

This invention relates to a table, a cot or 10 other supporting device which is adapted to remain level despite movements or variations in the position of the bottom or floor supporting the device.

This invention is set forth in the following 15 specification and claims and illustrated in the annexed drawing in which:—

Figure 1 is a side elevation of a table embodying this invention. Fig. 2 is an end elevation of Fig. 1. Fig. 3 is a section along 20 xx Fig. 1. Fig. 4 shows a modification.

This table can be used on ships or elsewhere. The table is provided with a top which remains in horizontal position when the ship pitches, and rolls.

25 In this drawing the letter a designates the legs of the table which are fastened to the deck or floor of a ship. These legs are provided with a series of slots b and each slot is engaged or coacts with a roller c . These 30 rollers are pivoted to standards d at each end of the table. The standards have a series of slots e which coact with rollers f pivoted to the hangers g fastened to the bottom of a table top h . The legs a being fastened to 35 the floor of the ship will rock when the ship pitches and the rollers will glide along the slots and assume a horizontal line thereby keeping the top level. The standards d which are placed at right angles to legs a 40 will take up the roll or side tilt of the ship and thus prevent the top from tilting or inclining with the floor or deck.

Applied to the hangers or standards d and g are brace pieces or bars i running respectively crosswise and lengthwise to the table proper or the top plate h . At these bars i at pivots m are suspended arms having weights k . These arms with weights k at their lower ends carry each a double pawl 50 of oppositely facing pawl teeth n .

The slotted portions or pieces b and e have their edges provided with teeth o arranged in a curve but none of such curves is concentric

with the pivots m . When the floor supporting the feet a rocks the table parts roll or 55 swing to maintain their various levels or perpendiculars.

When an edge or part of the table top h is overweighted as by a party leaning onto an edge or by an object placed on the top h the 60 bar i is tilted and the weight k swings to move a pawl tooth n to engage a tooth in rack o and arrest further movement in the direction in which a pressure onto the top h tends to swing the latter.

65 In place of rollers f balls Fig. 4 will serve as equivalents.

The operation is as follows:—If a pressure is exerted on a short edge of a table h the teeth o at guide piece b are engaged by their 70 pawl n . If the pressure is exerted on a long edge of the table the teeth o at guide piece e are engaged by the upper pawls n . The operation in each case is the same as a tilt of 75 table top h independent of legs a will cause the respective weight k which tends to remain hanging vertical to press a pawl tooth n into a rack tooth o .

The curved guide b can be distinguished as a fixedly arranged guide as its legs a cannot move unless the floor or deck supporting the same also moves or rolls while the guide e can move without the guide b moving.

What I claim is:—

1. A self - leveling - table comprising legs 85 fixed to a movable bottom and provided with guides, legs having anti-friction devices made to co-act with the guides and provided with a second set of guides arranged transversely to the first named guides and a table 90 top with hangers having anti-friction devices made to co-act with the second set of guides.

2. A table or support combined with 95 guides transversely arranged with respect to one another, rollers traveling along the guides, teeth along the guides, and pawls hung from the table so as to be moved to engagement by pressure thereon and lock the table against movement by such pressure.

3. A table or support combined with 100 curved guides arranged transversely to one another, table supporting rollers made to travel along the guides, teeth at the guides, pawls hung from the table eccentrically to the curvilinear arrangement of the teeth, and 105 a weighted swinging arm for the pawl for

causing the table top when exposed to pressure to swing a pawl to its teeth to lock the table against tilting.

4. A table or the like comprising fixedly arranged curved guide, a second curved guide movable on the first named guide, a table top movable on the second guide, a weighted pivoted pawl on the second guide for engaging the first guide as the table top is pressed out of level, and a weighted piv-

oted pawl on the table top for engaging the second guide as the table top is pressed out of level.

In testimony whereof I have hereunto set my hand in the presence of two subscribing ¹⁵ witnesses.

ROBERT G. MacKINNON.
